UNITED STATES PATENT OFFICE.

JOHN M. S. ANDERSON, OF BRIDGEPORT, CONNECTICUT, ASSIGNOR TO THE GENERAL MACHINE AND MANUFACTURING COMPANY, OF BRIDGEPORT, CONNECTICUT, A CORPORATION OF CONNECTICUT.

BOTTLE STOPPER.

1,421,118.

Specification of Letters Patent. Patented June 27, 1922.

Application filed January 14, 1921. Serial No. 437,285.

To all whom it may concern:

Be it known that JOHN M. S. ANDERSON, a citizen of the United States, and resident of Bridgeport, in the county of Fairfield and 5 State of Connecticut, has invented certain new and useful Improvements in Bottle Stoppers, of which the following is a specification.

This invention relates to new and useful 10 improvements in bottle stoppers, and the object of the invention is to provide a novel and durable stopper of extremely simple construction and consisting of a minimum number of parts.

15 With the above and other objects in view, the construction, arrangement and combination of parts constituting the stopper of the invention will now be fully described and will hereinafter be specifically claimed.

20 In the accompanying drawing forming a part of this specification,

Fig. 1 is a perspective view of the stopper, together with its bail;

25 Fig. 2 is a sectional view of the stopper and bail of Fig. 1;

Fig. 3 is a perspective view of the bail carrying member constituting an element of the stopper;

30 Fig. 4 is a top plan view of the stopper, with the bail removed; and

Fig. 5 is a bottom plan view corresponding with Fig. 4.

The stopper consists of but three specially 35 constructed parts; an elastic plug adapted to enter the neck of a bottle to fill the same and to firmly rest upon the upper edge of the bottle in ordinary manner; a sheet metal bail carrying member adapted to be socketed in the plug; and a sheet metal cap adapted to 40 bear against the upper surface of the elastic plug and provided with an opening to receive the head of the bail carrying member. As will be made clear, the bail passes beneath the head of its carrying member, above 45 the cap, and between the legs of the bail carrying member to effectively hold the cap to the elastic plug.

The plug may be made of any material 50 suitable for its purpose, and comprises a cylindrical portion 10 adapted to tightly fit within the neck of a bottle and a circular shoulder portion 11 adapted to rest firmly

upon the upper edge of the bottle. The plug is provided with a pocket 12 having an enlargement 13, both of circular configuration. 55

As hereinbefore mentioned, the bail carrying member is preferably made of sheet metal. The configuration of said member is more clearly disclosed in Figs. 2 and 3, it being of approximate inverted U-shape and 60 consisting of a head portion 14 having legs 15 which are bent outwardly near their extremities to provide feet 16 adapted to rest snugly in the enlargement of the pocket of the plug. The outer surfaces of the legs 65 of the bail carrying member preferably conform in shape to the configuration of the smaller portion of the pocket in the plug, and the feet extend in such direction from the legs that the upper and lower surfaces 70 and the outer edges of the feet snugly engage the walls which define the enlarged portion of the pocket, as will be understood.

When it is desired to insert the bail carrying member in the plug, the legs are pressed 75 slightly toward each other and inserted in the pocket until the feet are adjacent the enlarged portion of the pocket. The legs are then released and expand to normal position to seat the feet in the enlargement 80 in the manner hereinbefore fully described.

The pocket in the plug is of such depth that when the feet are seated in the enlargement of the pocket, the head of the U-shaped bail carrying member projects a slight distance above the upper surface of the plug. 85

17 denotes a cap, which, as hereinbefore mentioned, preferably consists of sheet metal. The cap is adapted to rest snugly against the upper surface of the elastic plug, 90 and is provided with an opening 18 adapted to freely receive the head and a portion of the legs of the bail carrying member, thus providing a passage way 19, defined by the head, the cap, and the legs, of proper size to 95 snugly receive the bail, denoted by 20. Opening 18 is preferably circular and allows the cap to freely seat upon the plug.

It will be obvious that the bail will hold the cap on the bail carrying member. When 100 now the bail is manipulated in any ordinary or preferred manner to secure the stopper onto a bottle, the bail is necessarily drawn firmly against the cap to cause the same to

firmlly bear against the entire surface of the plug. The plug, which is necessarily more or less elastic, is thus reinforced and rigidly held to the bottle, and the tighter the bail 5 may be drawn, the tighter will the cap grip the plug, as will be evident.

It will be seen that I have provided a dependable stopper consisting of but few parts, none of the metal elements of which 10 are required to be cast, the bail consisting of ordinary wire, and the cap and bail carrying member being preferably composed of sheet metal which readily lends itself to stamping in the production of these last 15 mentioned elements.

What I desire to claim is:

1. A stopper consisting of an elastic plug provided with a pocket having an enlargement, a bail carrying member of inverted 20 U-shape and comprising a head having legs from which feet extend in opposite directions, said legs adapted to enter said pocket and said feet adapted to seat in said enlargement, and said head adapted to project 25 beyond said plug, a cap adapted to rest upon the plug and provided with an opening to receive said head and a portion of said legs, said head, cap and legs defining a

passageway, and a bail adapted to snugly fit said passageway.

2. A stopper consisting of a plug adapted to fit a bottle, said plug having a pocket provided with an enlargement, a resilient U-shaped bail carrying member comprising a head having legs from which feet extend in opposite directions, said legs adapted to enter said pocket and to exert a yielding pressure against the wall thereof and said feet adapted to snugly seat in said enlargement, whereby said bail carrying member is removably seated in said plug, and said head adapted to project beyond said plug, a cap adapted to rest upon said plug and provided with an opening to receive said head and a portion of said legs, said 45 head, cap and legs defining a passageway, and a bail adapted to snugly fit said passageway and to normally bear against said cap.

Signed at Bridgeport, in the county of 50 Fairfield and State of Connecticut, this 29th day of December, A. D. 1920.

JOHN M. S. ANDERSON.
